UNITED STATES PATENT OFFICE.

RUDOLF HÖING, OF ESSEN, GERMANY.

SELF-CLEANING NOZZLE.

Application filed August 24, 1921. Serial No. 494,888.

To all whom it may concern:

Be it known that I, RUDOLF HÖING, a citizen of Germany, residing at Essen, Germany, have invented certain new and useful Improvements in Self-Cleaning Nozzles (for which I have filed applications in Germany, June 17, 1919; Belgium, March 8, 1921; Holland, March 30, 1921; France, March 8, 1921; Czechoslovakia, March 30, 1921; England, January 10, 1921), of which the following is a specification.

My invention relates to nozzles and in particular to spray nozzles operated by compressed air, water under pressure steam or some other medium. These nozzles have the drawback that their discharge openings easily become clogged by foreign substances in the operating medium. This drawback is particularly obnoxious where spray nozzles are used for the ventilation of mines. If the nozzles are clogged, they are usually cleaned by unauthorized persons so that their openings become too wide and consequently the consumption of compressed air or the like will become too high.

According to my invention, the nozzle is so constructed that it cannot become clogged. It is provided with a beaded head at the end of the nozzle behind which fine perforations or slots are provided in the body of the nozzle. The pressure medium, such as compressed air, can get into the passage of the nozzle while the foreign substances contained in it are diverted sideways by the beaded head of the nozzle. Preferably, the perforated portion of the nozzle is made conical.

The novel nozzle can be operated continuously and has good efficiency. In order to provide, in the ventilation of mines, an energetic motion of the air in the passages, preferably a funnel shaped diffuser is provided in front of the nozzle in the central opening of which there is an adjustable ring. Experience shows that by means of this diffuser a more energetic flow of the medium is effected than by the arrangement of the nozzle heretofore used.

In the drawing affixed to this specification and forming part thereof, a device embodying my invention is illustrated diagrammatically by way of example. In the drawings—

Fig. 1 is an elevation, partly in longitudinal section, of a ventilating device according to the present invention,

Fig. 2 is a section through the nozzle proper,

Figs. 3 and 4 are elevations of the nozzle showing different kinds of openings, 60

Fig. 5 is an end elevation,

Fig. 6 is an elevation of a nozzle for the ventilation of mines partly in section arranged in position in the ventilating pipe,

a is the pipe or casing and *b* is a nozzle tube inserted in an axial opening thereof and having an axial passage *f*. A frusto-conical portion *c* of the nozzle tube *b* extends freely in rearward direction into the pipe or casing *a*. Its narrow inner end 70 carries a protective head with walls diverging in the direction of flow of the medium supplied to the nozzle. The frusto-conical portion *c* is provided with a number of slots or perforations *e* which extend from its surface to passage *f*. The slots, which may be formed by sawing, may be in any desired position. They may be at an angle to the axis of the insertion, as illustrated in Fig. 2, they may extend in planes extending through the axis, as illustrated in Fig. 3, or they may be at right angles to it, as illustrated in Fig. 4. The slots may intersect each other. Instead of slots, fine perforations may be provided which may also intersect. These 80

slots or perforations are always open to conduct the medium under pressure into the insertion if the opening of passage *f* is clogged. The foreign substances drawn into tube *r* (Fig. 1) will be thrown to one 90 side by the head *d* while the medium under pressure enters the passage *f* through slots *e*. The foreign substances will collect in the casing of the nozzle and are removed from time to time by means of a pipe *g* 95 provided with a cock *h*. For example, they may be blown out by means of the pressure medium.

In the device illustrated in Fig. 6, a diffuser *m* is provided in front of the nozzle *b* 100 in the opening of which is an adjustable ring *o*. This provides a considerably better current of air in the air passage *p*. The ring *o* can be adjusted axially in order to more or less concentrate the stream of compressed air which is discharged by the nozzles *a*.

The ring *o* is so adjusted that the most convenient discharge of air is effected.

I claim;

1. Spray nozzle comprising in combination a pipe or casing adapted to be supplied

- with a medium under pressure, a nozzle tube disposed in an axial opening of said pipe or casing, a frusto conical portion of said nozzle tube extending freely rearwards into said pipe or casing and being provided with narrow apertures extending into the interior of said nozzle tube and a protective head with conically diverging walls at the inner narrow end of said tapering portion.
- 10 2. Spray nozzle comprising in combination, a pipe or casing adapted to be supplied with a medium under pressure, a nozzle tube disposed in an axial opening of said pipe or casing, a frusto-conical portion of said nozzle tube extending freely rearwards into said pipe or casing and being provided with narrow apertures extending into the interior of said nozzle tube, a protective

head with conically diverging walls at the inner narrow end and a diffuser in front of 20 said nozzle tube.

3. Spray nozzle comprising in combination, a pipe or casing adapted to be supplied with a medium under pressure, a nozzle tube disposed in an axial opening of 25 said pipe or casing, a frusto conical portion of said nozzle tube extending freely rearwards into said pipe or casing and being provided with narrow apertures extending into the interior of said nozzle tube, a protective head with conically diverging walls at the inner narrow end, a diffuser in front of 30 said nozzle tube and a mouth-piece adjustably disposed in said diffuser.

In testimony whereof I affix my signature.

RUDOLF HÖING.
